Inventor:
Jesse C. Garretson

UNITED STATES PATENT OFFICE.

JOEL C. GARRETSON, OF PILOT GROVE, IOWA.

IMPROVEMENT IN THE MANUFACTURE OF SUGAR FROM SORGHUM.

Specification forming part of Letters Patent No. 38,958, dated June 23, 1863.

To all whom it may concern:

Be it known that I, JOEL C. GARRETSON, of Pilot Grove, in the county of Lee and State of Iowa, have invented a new and Improved Process or Mode of Making Sugar and Molasses from the Sorghum or Chinese Cane; and I do hereby declare that the following is a full and exact description thereof, reference being had to the accompanying drawing, and to the letters of reference marked thereon.

The nature of my invention consists in the arrangement and combination of the grading-pans, shutters, partitions, and skimmer extending over the apartments, and for the purpose of more easily grading and granulating sugar from sorghum.

To enable others to make and use my invention, I will proceed to describe the construction and operation of the same.

The figure represents the boiler and general skimmer in perspective.

A represents transverse partitions in the boiler.

B represents apartments in the boiler.

C represents apertures near the ends and bottoms of partitions A.

D represents shutters working on pivots to open and close the apertures at C.

E represents the emptying-spout.

F represents the general skimmer.

G represents the handle of general skimmer at F.

I represents slots in the lower edge of general skimmer and resting on partitions A, and on which it slides.

To commence operations, partly fill the boiler with common water and place it over a common furnace. When the water has commenced boiling the juice is then allowed to flow from a reservoir or tank into the boiler at apartment B', where it is boiled and skimmed to a certain grade, when shutter D, at A', is opened and the juice flows through the aperture C into the next apartment, B, where it is boiled and skimmed to another grade higher, when the next shutter, D, is opened and the next apartment is filled, and so on until all the apartments are full, and the sirup in the last and finishing apartment is reduced to the con-

sistency of common molasses. The spout E is then opened and the sirup is passed out into a receiver or cooler. The spout is then closed and the apartment is again filled from the next apartment, the shutter closed, and the next in order opened and closed, until all the apartments are filled with juice or sirup. Add, now, some more common water to all the apartments, except the finishing one, skim, and proceed as before described. The sirup is clear and palatable when thus manufactured, and granulates readily.

The general skimmer F is operated by taking hold of the handle G, pressing it forward and downward toward the operator, sliding the skimmer to the opposite side of the boiler, raising the handle again and draw it toward the operator, which will bring the skum in a compact form to the side of the boiler next to the operator, when the skum is removed by a hand-skimmer used for that purpose, which should be rinsed in common water every time it is used in a different grade of sirup to prevent carrying the green scum and other impurities from one grade to another. The sirup is conveyed from the cooler or receiver to the wide shallow tanks, and covered with thin canvas to secure it from dust, when it will, by the action of the atmosphere, granulate in a short time into mush sugar. At this stage a small quantity of common water is poured into the tank and stirred with the sugar a short time briskly. It is then dripped and dried in any of the usual forms. By this process an excellent article of sugar and molasses is produced.

What I claim as my invention, and desire to secure by Letters Patent, is—

The arrangement and combination of the grading-pans B, with shutters D at the end of each partition A, with skimmer F, extending over all the apartments B, arranged and combined for the purpose of grading and granulating sugar, in the mode and manner described.

JOEL C. GARRETSON.
